Primary Examiner—Antoine Duval Davis(74) **Attorney, Agent, or Firm**—Foley & Lardner**CLAIM**

The ornamental design for a safety cone, as shown and described.

DESCRIPTION

FIG. 1 is a frontal perspective view of a safety cone according to my new design;

FIG. 2 is a front view thereof;

FIG. 3 is a back view thereof;

FIG. 4 is a right side view thereof;

FIG. 5 is left-side view thereof;

FIG. 6 is a top view thereof; and,

FIG. 7 is a bottom view thereof.

The ornamental design which is claimed is shown in solid lines in the drawings. Any broken lines in the drawings are for illustrative purposes only and form no part of the claimed design.
